UNITED STATES PATENT OFFICE

EDWARD T. BIRDSALL, OF CLEVELAND, OHIO, ASSIGNOR TO THE BUTLER MANUFACTURING COMPANY, OF CLEVELAND, OHIO, A CORPORATION OF OHIO

STREET SWEEPING APPARATUS

Application filed May 26, 1924, Serial No. 715,881. Renewed April 6, 1931

This invention relates to street sweeping machines, and more particularly to machines of the pneumatic or vacuum type which are propelled along the streets and which, as they travel therealong, sweep up the refuse, separate the lighter particles of refuse from the air, and discharge the cleansed air into the atmosphere, and collect the refuse. One of the general objects of the invention is to provide a practical, sanitary and dustless machine of this character which is capable of sweeping the streets efficiently, without the need of spraying or wetting the streets before the sweeping operation and without the need of spraying or treating the material after it is taken into the machine—the machine, however, being capable of use in either dry or wet weather. Other general objects of the invention are: to provide a machine which is capable of operating in close proximity to the curbs and of removing rubbish efficiently from the gutters alongside such curbs; to provide an improved means for driving, from the crank, or engine, shaft, the various operating parts of the machine; to provide a simple, efficient and strong construction of frame or chassis for such sweepers; to provide efficient means for mounting and adjusting the broom; to provide an improved mounting for the broom-housing; and, to provide an improved construction and arrangement of parts for handling the material separated from the dust-laden air. Further and more limited objects of the invention will appear hereinafter and will be realized in and through the construction and arrangement of the parts shown in the drawings, wherein Fig. 1 represents a side elevation of a sweeping machine constructed in accordance with my invention; Fig. 2 a sectional side elevation of such machine, the chassis being shown in elevation; Fig. 3 a plan view, and Fig. 4 a side elevation, of the frame or chassis; Fig. 5 a detail in section corresponding to the line 5—5 of Fig. 3; Fig. 6 a sectional plan view showing the mechanism for transmitting the drive from the engine or crank-shaft to the rear wheels and to the various sweeper mechanisms of the machine; Fig. 7 a diagrammatic view of the

rear portion of the machine, illustrating the manner in which the frame is offset on the right hand or curb side thereof for access of the broom to curbs and gutters; Fig. 8 a plan view of the hoppers which collect the lighter refuse separated from the dust-laden air, the door-closing springs being omitted; Fig. 9 a sectional view corresponding to the line 9—9 of Fig. 8; Fig. 10 a detail in section showing the manner of constructing and mounting the end of the arms which close the hopper doors; and Fig. 11 a diagrammatic plan view showing the means for raising and lowering the broom.

Describing the various parts by reference characters, A represents a truck or carriage which is adapted to be propelled along the ground or street in the usual manner; that is to say, by means of an engine X, drive or crank shaft 1 (see Fig. 6), suitable transmission gearing (not shown) in a transmission box or housing 2, and a propeller shaft 3, connected by a universal joint 4 with the transmission shaft 5, the propeller shaft driving the rear axle in the usual manner and the latter driving the rear wheels 6. The truck is provided with a housing, indicated at B and enclosing the passages through which the rubbish and the dust-laden air are conducted, the endless belt or conveyor which handles the rubbish, the tubes which separate the dusty material from the air, and the hoppers into which such material is delivered.

Projecting rearwardly from and constituting extensions of the housing B are the fan housing C and the broom housing D. The housing D is of appropriate shape for the mounting therein of the rotary broom E, the casing being open at the bottom and being flexibly connected to the housing B by means of a bellows-like connection E'. The housing D is movably supported by means of a U-shaped frame F, the front ends of the arms of the frame being pivoted to the rear ends of the chassis side members 7, as indicated at F'. This frame is riveted or otherwise suitably secured to the housing and the rear of the frame carries a caster wheel 8 at each side thereof, the frame being connected to the

rear side of the housing D by means of straps 8^a projecting from the caster-wheel mountings and secured to the bottom reinforcing member 8^b on said housing. The construction described enables the housing D to move up and down about the pivots F' and to accommodate itself and the broom therein to irregularities in the road or pavement.

The broom is mounted upon a shaft 9 the opposite ends of which are mounted in journal blocks 9^a which are slidably mounted in vertical guides 10, at the opposite sides of the housing D. Each journal box is mounted on a rod 11, the upper ends of the rods extending through transverse guide members 12. The rods are intended to be operated in unison to raise and lower the shaft 9 and the broom. For this purpose, I prefer to use a transversely extending worm shaft 13 having worms 13^a thereon adapted to mesh with worm gears 11^a on the rods 11, within the guide members 12. The left hand end of the shaft 9 is provided with a pulley 9^b for driving the same.

For the purpose of facilitating the delivery of rubbish into the housing B, the lower front portion of the latter is made in the form of an arcuate dust pan 14, which extends from side to side of the forwardly projecting side extensions D' of the housing D, said extensions constituting lower rear extensions of the housing B and having their lower edges in close proximity to the road or pavement. The lower end of the dust pan is adapted to ride upon the ground or pavement and its upper end is secured to a plurality of brackets 15 carried by a rock shaft 16 which is mounted in journals 17 carried by the rear transverse frame 18 of the chassis (see Figs. 2 and 3). The rock shaft is provided with an operating arm 19 which is connected by a suitable cable 20 with the lower arm 21^a of a lever, pivoted at the front of the housing B, as indicated at 22, the upper operating arm of the lever being indicated at 21, in convenient position for operation by the driver. Should the sweeper be passing over an obstruction which it is undesirable that the dust pan should strike, or should it be desired to back the vehicle, the pan may be swung upwardly out of the way by merely pulling upwardly on the lever arm 21.

Within the housing C is the fan G which draws up the dust-laden air from the space within the housing B below the rear hopper H into the fan housing and discharges the same into a distributing passage or chamber J located above a series of dust-separating tubes K, the lower ends of which are located above the hoppers H and H'. The sides of the vehicle body are provided with discharge openings or slots L located below louvers L'. The tubes consist of thin but closely-woven cloth which will allow the air to pass through the meshes thereof, but which will

retain the finest dust. The tubes may be mounted in any desired manner, the details of construction and the manner of mounting the same constituting no part of this invention.

The fan G is provided with a shaft 22 which extends through the sides of the housing C and is provided at the left hand end with a pulley 23.

Reference has been made to the hoppers H and H'. The first mentioned hopper is the principal hopper and receives the greater portion of the material delivered through the tubes K, the hopper H' receiving the portion delivered through the front tubes. The hopper sections are provided with a common intermediate bottom member H^a. The hopper H is provided with a door 24 and the hopper H' with a door 25, respectively, which doors are adapted to be opened from time to time by mechanism and under conditions to be described hereinafter.

Adjacent the front of the housing B, the side members 7 are connected by a transverse metal plate 26, the edges of the said plate being strengthened by means of angle irons 27 secured thereto. Deep angle iron brackets 28 are secured to the plate 26 by flanges 28^a and secured to the said members by means of flanges 28^b, and brace the projecting ends of the plate. This plate not only strengthens the chassis construction but provides a platform for cans or receptacles 29 which are insertible into and removable from the housing B, by means of an opening or openings provided in the side or sides thereof and closed by a suitable door or doors. The cans or receptacles 29 are arranged below the hopper H', the rear can or receptacle being shown directly beneath the upper end of an endless conveyor 31 which is so located as to receive heavier refuse delivered thereto by the broom E and from the hopper H and to deliver such refuse into the said can or receptacle. This conveyor is mounted on suitable rollers 32 (driven by means to be described hereinafter) and passes over upper intermediate supporting idle rollers 33 and over lower idle rollers 34 and 35.

Beneath the roller 35 is a light canvas apron 36 mounted upon a rod 36^a, the purpose of this apron being to prevent material being driven therebeyond by the broom should the dust-pan be raised, as by striking an obstruction.

The hopper doors 24 and 25 are normally retained closed by means of arms 37 each adjustably secured to a rock shaft 38 by means of jaws 37^a and bolts 37^b. Each rock shaft is provided with an arm 39, the said arms being connected by a cable 40. Connected with the front rock shaft 38 is an operating arm or lever 41, extending in convenient relation to the seat M. A spring 42 is connected to the arm 37 at the front of the hopper, extending through the door 25 for this purpose,

and a like spring 43 is connected to an extension 37^c of the arm 37 which closes the rear door 24. These springs serve to hold in door-closing position the arms with which they respectively cooperate and to close the doors when the driver releases the operating lever 41. The inner end of each arm 37 is provided with a roller 44 (see Figs. 9 and 10); and the roller-provided end of each lever projects 10 into a housing 45, secured to the appropriate door, the said housings being U-shaped in section and each having its larger opening presented toward the shaft 38 adjacent thereto.

The broom, the conveyor, and the fan are 15 driven from the engine or crank shaft by means of a power-takeoff located in front of the main clutch as well as in front of the transmission gearing, enabling the said broom, conveyor, and fan to be driven irrespective of the movements of the truck. To 20 accomplish this result, the following construction is provided:—The pulley 23 on the fan shaft 22 is driven by means of a belt 46 passing over a pulley 47. The pulley 9^b on the 25 broom shaft 9 is driven by a belt 48 passing over a pulley 49. The pulleys 47 and 49 are mounted respectively on shafts 47^a and 49^a, each having a sprocket 50 and 51, respectively, thereon; and the driving roller 32 at the upper 30 end of the conveyor 31 is provided with a shaft 32^a having a sprocket 52 thereon. These sprockets are driven by means of a transverse shaft 53 having a sprocket 54 thereon and a sprocket chain 55 extending 35 around all of the said sprockets, the shaft 53 thus driving the broom, conveyor and fan and being itself driven from the engine shaft independently of the main clutch and transmission gearing as will be pointed out herein- 40 after.

For the purpose of automatically taking in the slack of the belts 46 and 48, belt-tightening pulleys are provided. One of these pulleys 56 is mounted on a lever 57 which is pivoted intermediate of its ends at 58 and is adapted by upward movement of the lever arm 57 to press against the lower reach of the belt 46. The other pulley 59 is mounted on one arm 60 of an angle lever which is pivoted at 61 and which is adapted, by a downward movement of the arm 60, to press against the upper reach of the belt or rope 48. The other arms 57^a and 60^a of these levers are connected by a spring 62 and rods 63 connecting the ends of the springs with the respective lever arms 57^a and 60^a. This construction insures a non-slipping drive between the belts 46 and 48 and their cooperating pulleys.

Returning now to the manner of driving 60 the broom, conveyor and fan from the engine shaft through the shaft 53, attention is invited to Fig. 6. In this view, the engine shaft or crank shaft 1 extends into a housing 64. This housing terminates in a bell-housing 65 containing the fly-wheel 66 and the ordinary

clutch 67, at the rear of which is located the transmission box 68 containing the ordinary transmission gearing (not shown) and into which the transmission lever 69 extends. From the rear of the transmission box there 70 extends the transmission shaft 5 which is connected by a universal joint 4 with the propeller shaft 3, as explained hereinbefore.

Between the fly-wheel 66 and the clutch 67, the shaft 1 is provided with a gear 70. 75 Mounted in bearings 71 provided at one side of the bell housing is one end of a counter-shaft 72, the said shaft being provided with a gear 73, by means of which and a silent chain 74, the shaft is driven from the shaft 1 through the gear 70. The parts 70, 71, 73 and 74 are all mounted within the bell housing. 75 denotes a shaft at the rear of the shaft 72 and provided with a miter gear 76 which meshes with a miter gear 77 on the shaft 53, the adjacent ends of the shafts 53 and 75 and the miter gears thereon being enclosed within a housing 78 which is fastened to the lower side of the plate 26. 79 denotes a clutch for connecting the shafts 72 and 75, 80 the clutch being provided with a collar 80 which is operated by a rod 81 pivoted at one end to one of the side frames 7 and connected at its other end by means of a link 82 with a lever 83 having its operating end in convenient relation to the seat M. It will be evident that, by virtue of the construction and arrangement of the parts described, the broom, conveyor and fan can be driven from the engine shaft irrespective of the main clutch 85 and transmission by means of which the propeller shaft is operated.

The machine shown herein is intended for sweeping gutters and for operating in close proximities to curbs. With that object in view, it will be noted that all of the projecting parts are on the left or street side of the machine, with the sole exception of the link 40 which connects the arms 39 for simultaneously opening the front and rear hopper doors; while the rear portion of the chassis is offset on the right hand side a greater distance than the projection of such link, such offsetting enabling the broom to operate in practical contact with the curbs. The manner in which this offsetting is accomplished will be apparent from an inspection of Figs. 3, 4 and 7. The side members 7 terminate a considerable distance in front of the rear of the housing B and also in front of the broom. 100 A generally rectangular frame 18 is secured to the rear ends of the side members 7, the front member 84 of such frame being secured to said side members by means of gusset plates 85. The rear member 86 of said frame carries the journals 17 for the rock shaft 16 while the front member carries the bearings 87 for the studs or pins F' which pivotally support the forward ends of the arms F. The 105 downwardly and rearwardly extending side 110

members 90 of the rectangular frame are provided with bearings 91 for the shackles 92 which support the rear ends of the springs 93; also with bearings 94 for the roller 35; 5 also with bearings 95 for the roller 32. The rear member 86 is extended beyond the front member 84 at the right hand side of the chassis, as indicated at 96. The opposite ends of the member 86 carry the uprights 97 and 98 10 to which the rear vertical corner members of the housing B are secured; and an inwardly and forwardly extending member 99 connects the upright 98 with the front member 84 of the frame, the member 99 being formed as a 15 flange on the side member 90. The inclination of the member 99 is such as to offset the rear part of the frame 18 about three inches to the right, with the result that the right hand side of the rear of the machine is offset 20 a corresponding amount, enabling the right hand edge of the broom to operate in substantial contact with curbs, thereby to sweep gutters in an efficient manner. This will be apparent from Fig. 7, wherein the right hand 25 side D' of the broom housing is shown as extending rearwardly from the vertical corner member 100 which projects upwardly from the upright 98.

30 The plate 26, in addition to forming the only intermediate cross member connecting the said members 7 and connecting the platform for the receptacles 29, constitutes a support for the front end of the housing B, the housing being supported from the four corners of the said plate by means of the angle irons 101 which form vertical posts, the said angle irons being secured to the housing and to the said plate.

35 With the parts constructed and arranged 40 as described, it is believed that the operation will be readily understood. Assuming that the engine is running, when it is desired to operate the sweeping mechanism it is necessary only to operate the clutch 79 by the 45 lever 83 to connect the shafts 72 and 75. This will drive the shaft 53 and, through the chain 55 and sprockets 50, 51, 52 and 54, will drive the fan, the broom, and the endless conveyor 50 31. The heavy refuse material will be delivered by the broom upon the conveyor and will be conducted by the latter to one or more of the receptacles 29. The lighter particles, suspended in the air, will be drawn into the fan casing C and forced by the fan G into the distributing chamber J. The air will be forced laterally through the tubes K and will be delivered, thoroughly cleansed, through the discharge openings L below the louvers L'. The refuse material that was in 55 suspension in such air will be collected by the tubes and discharged into the hoppers H and H'. From time to time, as occasion 60 may require, the doors 24 and 25 will be opened by the driver by operating the lever 65 41. Material in the hopper H' will be dis-

charged directly into the receptacle 29 therebeneath, while the material in the hopper H will be discharged upon the conveyor and delivered by the latter into one or more of the said receptacles.

70 By locating the power takeoff for the fan, broom and conveyor, in front of the main clutch 67, I am enabled to operate the sweeping and separating mechanism at any time when the engine is running and irrespective 75 of whether the truck is being driven as well as of the manner in which the same is being driven. This is decidedly advantageous, and particularly where the matter to be cleaned is packed in such manner as to require a 80 longer brushing operation than will be afforded by merely driving over the particular spot or zone where such has accumulated. Furthermore, it permits me to suspend the operation of the sweeping and separating 85 mechanism when passing over a street or section of street which has already been cleaned. It also makes it possible to operate the sweeping and separating mechanism when the vehicle is being backed, as the fan, broom and 90 conveyor are always operated in the same direction by reason of the location of the power takeoff in advance of the transmission gearing.

95 Should it be necessary or desirable to adjust the position of the broom with reference to the road or pavement, this adjustment can be conveniently and quickly obtained by means of the shaft 13. The purpose and advantages of the dust pan 14 and the manner 100 of mounting the same have been pointed out hereinbefore; so also have the purposes and advantages of the belt-tightening mechanism and the offsetting of the rear right hand side of the housing and broom, with 105 the absence of projections on such side of the machine.

110 It will be evident that by reason of the construction and arrangement of parts shown and described herein, I have produced a machine, which is easily and conveniently operable, which is capable of cleaning 115 streets in an efficient manner, and which will meet and withstand all ordinary incidents of use.

115 Having thus described my invention, what I claim is:—

1. In a street-sweeping machine, the combination, with a chassis having driving wheels, of an engine on said chassis, a shaft 120 driven by said engine, means including a clutch and transmission gearing for operating the driving wheels from the said shaft, a housing on said chassis, a broom carried by the chassis and arranged to sweep refuse into 125 said housing, air-moving means in said housing, a shaft additional to the first shaft, driving connections between the second shaft and the said broom and air-moving means, and connections for driving the second shaft from 130

the first shaft, the said connections being arranged in front of the clutch and transmission gearing whereby the broom and the air-moving means may be operated irrespective of the movements of the said machine.

5. 2. In a street-sweeping machine, the combination, with a chassis having a housing thereon, of an engine and driving wheels, a shaft driven by said engine, means including a clutch and transmission gearing for operating the driving wheels from the said shaft, a broom arranged to deliver refuse into said housing, air-moving means and dust-separating means in said housing, a conveyor arranged to receive refuse from said broom, a shaft additional to the first shaft, driving connections between the second shaft and the said broom, the conveyor, and the air-moving means, and power take-off mechanism connecting the second shaft with the first shaft in front of the said clutch and transmission gearing whereby the broom, the conveyor and the air-moving means may be operated from the first shaft irrespective of the movements of the said machine.

25. 3. In a street-sweeping machine, the combination, with a chassis having driving wheels and a housing, of an engine on said chassis having a shaft, means including a clutch and transmission gearing for operating the driving wheels from the said shaft, a shaft additional to the first mentioned shaft and the wheel-operating means, a broom for delivering refuse into said housing, air-moving and dust-separating means in said housing, power take-off mechanism connecting the second shaft with the first shaft in advance of the said clutch and transmission gearing, and means, including a clutch, for driving the said broom and the said air-moving means from the second shaft.

40. 4. In a street-sweeping machine, the combination, with a chassis having a housing and driving wheels, of an engine mounted on said chassis and having a shaft, means including a clutch and transmission gearing for operating the driving wheels from said shaft, air-moving means carried by the said chassis, street-sweeping means adapted to deliver refuse into said housing, a conveyor for refuse in said housing, a shaft additional to the first shaft and the connections for operating the driving wheels, power take-off mechanism connecting the second shaft with the first shaft in front of the said clutch and transmission gearing, a shaft additional to the first two shafts, driving connections between the last mentioned shaft and the said conveyor and the said sweeping and air forcing means, and means including a clutch for driving the last mentioned shaft from the second shaft.

45. 5. In a street-sweeping machine, the combination, with a chassis having a housing and driving wheels, of an engine mounted on said chassis and having a shaft extending rear-

wardly from said engine, a bell housing into which said shaft extends, a flywheel on said shaft within said bell housing, means including a clutch and transmission mechanism for operating the driving wheels from the said shaft, a shaft having one end journaled in the bell housing, driving connections, also located in said bell housing and in front of said clutch, for driving the second shaft from the first shaft, a third shaft, dust-separating means carried by said chassis in said housing, sweeping and air-moving means also carried by the said chassis in said housing, connections for driving the said sweeping and air-moving means from the last mentioned shaft, and means including a clutch for driving the last mentioned shaft from the second shaft.

50. 6. In a street-sweeping machine, the combination, with a chassis having driving wheels, of an engine mounted on said chassis and having a shaft, a bell housing into which said shaft extends, means including a clutch and transmission mechanism for operating the driving wheels from the said shaft, journal bearings at one side of said housing, a shaft having one end mounted in said bearings and extending rearwardly therefrom, a gear on the first shaft in said housing, a gear on the second shaft between the bearings in said housing, a chain in said housing connecting said gears, the first gear being located in front of said clutch, sweeping and air moving means carried by the said chassis, and connections for driving the said sweeping and air-moving means from the second shaft.

55. 7. In a street sweeping machine, the combination with a chassis having driving wheels, of an engine carried by said chassis and having a crank shaft, a rearwardly extending drive shaft for said wheels, a clutch forming a driving connection between said engine crank shaft and said drive shaft and including a transmission, a housing on said chassis, a broom arranged within said housing and disposed so as to sweep refuse within said housing, air moving means connected with said housing and including a shaft for operating the same, driving connections for said broom and air moving means, said driving connections being arranged in advance of said clutch and directly connected with said crank shaft whereby the broom and air moving means may be operated entirely independent of said clutch, transmission and drive shaft.

60. 8. In a street sweeping machine, the combination with a chassis having driving wheels, of an engine having a crank shaft, means including a clutch, a transmission and a drive shaft for driving said wheels from said engine, a housing carried by said chassis, a shaft journaled in said housing and having a broom thereon, air moving means communicating with said housing, a counter shaft disposed parallel with said crank shaft and operatively

connected with said broom shaft and air moving means, and a positive direct driving connection between said crank shaft and counter shaft whereby said broom and air moving means are operated entirely independent of said clutch, transmission and drive shaft.

9. The combination, with a chassis having driving wheels, of an engine on said chassis, a crank shaft driven by said engine, means including a clutch and transmission for operating the driving wheels from said crank shaft, a countershaft extending substantially parallel with the crank shaft, mechanism carried by said chassis and connections for driving said mechanism from said countershaft, a driving connection between said crank shaft and the countershaft in advance of said clutch and transmission, a housing enclosing said driving connection and having bearings for the adjacent end of the countershaft, a housing constituting an extension of the first mentioned housing and enclosing the clutch and transmission and having its open front end registering with an opening in the rear of the first housing, and a partition interposed between said housings and constituting a bearing for the portion of the crank shaft adjacent the clutch and separating the driving connections between the crank shaft and the counter shaft from the clutch and transmission.

10. The combination, with a chassis having driving wheels, of an engine including a crank case and a crank shaft therein mounted on said chassis, a fly wheel on said crank shaft, a housing attached to said crank case and enclosing the fly wheel, a closure for said housing through which an extension of the crank shaft extends, a transmission, a clutch connecting the crank-shaft extension and the transmission, a second housing enclosing the transmission and the clutch and attached to the first mentioned housing, a propeller shaft connecting the transmission and the driving wheels, a countershaft extending into the first-mentioned housing, driving connections between the crank shaft and the countershaft for constantly driving the same with the crank shaft, the said connections being within the first-mentioned housing and interposed between the fly wheel and the clutch, mechanism carried by said chassis, and driving connections including a clutch between said mechanism and said countershaft.

In testimony whereof, I hereunto affix my signature.

EDWARD T. BIRDSALL
